RECEDING CHAIR FOR THEATERS AND
THE LIKE

Elias S. Diehl, Bedford, Pa.

Application July 1, 1946, Serial No. 680,630

5 Claims. (Cl. 155—115)

1

The present invention relates to ways and means to facilitate freedom of movement of incoming and outgoing persons in passageways between closely related rows of theatre chairs, especially when the chairs are occupied and available space for passers-by is limited, results desired being obtainable through the use of occupant controlled receding chairs.

It is a matter of common knowledge that in order to conserve space and to handle and serve capacity audiences theatres, auditoriums and similar places of amusement, are generally such that passageways leading laterally from the main aisles between rows of chairs are narrow and needlessly limited. This is especially so when, with the chairs of the row wholly or partly occupied, incoming and outgoing passers-by meet with well-known obstructions. As a matter of fact and due to space limitations all concerned are disturbed and exasperated, and with these and other inconveniences in mind, I contemplate the adoption and use of receding individually shiftable chairs, the latter, when shifted rearwardly and regulated by the occupant, serving to sufficiently widen the passageway to allow for expeditious and convenient movements of passers.

Briefly, and in carrying out the preferred embodiment of the invention, I provide an especially constructed frame in which the chair is shiftably mounted, the details of construction being such that the chair, when set in motion, is rearwardly movable but is also lifted and elevated from a low to high position, whereby to clear the legs of the occupant immediately in the rear of the momentarily shifted chair.

In carrying out the principles of the invention, I have planned and worked out a number of embodiments, these stemming from the common thought of utilizing a fixed frame structure and a chair movably mounted therein, the chair being of an ordinary type but the means for mounting it being such that the chair rides back and forth to achieve the desired results and, in so doing, is shifted by mechanical devices so that in its rear-most position the seat of the chair assumes a position elevated sufficiently to avoid contact with the occupant of the chair immediately in the rear of the shifted chair.

I aim, in carrying out the simplest embodiment of the invention, to provide a structure in which the occupant simply catches ahold of the seat and, while gradually rising to a standing position, pushes same rearwardly, said seat having legs and said legs having rollers operable in inclined tracks or ramps, thus causing the chair, as a unit, to

2

glide or shift rearwardly and to rise to an elevated plane and to thereafter return, by gravity, to a normal seating position.

In addition to the above, it is an object of the invention to carry forward the same basic principles and to incorporate special button controlled hydraulic or air powering devices, whereby to utilize the latter instead of manual effort in achieving desired ends.

10 It is also within the spirit and sphere of the invention to employ other powering means and devices for lifting and lowering purposes and it is therefore another object of the invention to utilize, in certain instances instead of the hydraulic jack devices, an electric motor and sprocket chain drive, this as hereinafter described.

Other objects, features and advantages of the invention will become more readily apparent from 20 the following description and the accompanying illustrative drawings.

In the drawings wherein like numerals are employed to designate like parts throughout the views:

25 Figure 1 is an assembly view showing, at the center, a chair of one row and showing, in addition, chairs in adjacent rows, one in front and one in back, this to illustrate the receding and clearance principle of operation.

30 Figure 2 is a front elevational view of a receding chair constructed in accordance with the principles of this invention, the same being shown in its normal "at rest" position.

Figure 3 is an enlarged detailed section taken 35 approximately on the plane of the line 3—3 of Figure 1.

Figure 4 is a view similar to Figure 1 with one of the side frames removed to show the construction and adaptability of the lower parts of the 40 structure.

Figure 5 is a rear view of Figures 1, 2 and 4.

Figure 6 is a fragmentary perspective view of the central portions of the base of the frame structure.

45 Figure 7 is a view similar to Figure 4 but showing a modification in which a pivoted jack is employed as a mechanical lifting device.

Figure 8 is a section occurring approximately on the plane of the line 8—8 of Figure 10.

50 Figure 9 is a view similar to Figure 8 with portions of one of the uprights broken away to show internal track means.

Figure 10 is a cross-section on the vertical line 10—10 of Figure 7, looking in the direction of the 55 arrow.

Figure 11 is a view in elevation and section showing the piping arrangement with control valves for the fluid.

Figure 12 embodies a modification in the construction wherein an electric motor is used as a powering device or prime mover for operating mechanical means to lift and lower the chair in relation to the frame, and

Figure 13 is a view of Figure 12 observing same in a direction from right to left, portions being broken away and shown in section to disclose certain of the structural details.

Attention is directed first to the manually operable chair and frame structure forming one of the simplest embodiments of the invention illustrated in Figures 1 to 6 inclusive. Reference being had first to Figure 1, this figure, as before indicated, is employed to show the relationship of chairs in three rows to bring out the receding and clearance principles. That is to say, there is a chair in one row A which may be said to be the rear row, a chair B in what may be designated a front row and then the remaining chair C, intermediate row, fully drawn to bring out the complete construction and also the mode of operation in full and dotted lines. It was thought advisable, in preparing the drawings, to show a three row arrangement in order to illustrate the principle of operation and to simply show the chairs in the rows A and B in fragmentary form. However, the invention is not so much in the idea of a receding and elevated chair as it is in the particular construction of the chair itself.

Referring now to the drawings by detailed reference numerals it will be seen that the relatively stationary frame is denoted by the numeral 15 and this comprises a base frame (see Fig. 6) including transverse end members 16 and front and rear connecting straps or members 17 and 18. The numerals 19 designate inclined risers or ramps with longitudinally curved grooves 20 forming tracks. The numerals 21 designate relatively fixed uprights connected at their upper ends to horizontal arm rests 22.

The chair, as a unit, is denoted by the numeral 23 (see Fig. 4) and comprises a suitably cushioned seat 24 and a back rest 25, the back rest being hingedly mounted in any suitable manner as indicated at 26. The seat is provided with rigid X-shaped legs 27 with a reinforcing and spacing rod 28 connecting same. The X-shaped legs or leg frames are inwardly of the uprights 21 and also inwardly of the ramps 19 and in fact ride in slidable contact with the inner faces of said ramps. As brought out in Figure 3, the lower ends of the legs are provided with anti-friction chair shifting and lifting rollers 29 operable in the grooves or tracks 20. Suitable bolts 30 are employed as journals for the rollers 29 and these are threaded into the legs and have smooth shank portions 31 which serve as anchor pins for eyes 32 on the resilient straps 33. These straps, it will be noted, are shaped and arranged as shown in Figures 1, 4 and 5. That is to say, the straps have their curved upper ends rigidly mounted just above the hinge means on the back rest of the chair. The lower front ends of the straps extend beneath the seat and down between the tracks where the eyes 32 movably embrace the anchor pins 31. The means 31 and 32 form hinges for the lower frontal ends of said straps 30. The purpose of these straps is to cause the back rest to raise in approximately normal line compared to the "at rest" full line position seen in Figure 1. In accordance with the construction just de-

scribed, it will be seen that by catching a hold of the seat and pushing same from right to left in Figure 1, the rollers 29 ride in the tracks or grooves 20 and follow the arc or curvature of said tracks and in so doing, the seat moves from a horizontal position to the tilted or inclined dotted line position illustrated in Figure 1. However, due to the connecting straps 33 between the back rest and the anchor pins 31, the back rest moves up in the same line, thus rendering the operation successfully accommodating to intended purposes. It is desired, obviously to hingedly connect the back rest and seat and to provide this link or strap connection between the hinged back rest and seat and leg frame structure to cause the back rest and seat to take the angular relationship seen in Figure 1. The seat not only recedes but tilts and this tilting movement is sufficient, ordinarily, to provide leg clearance for the occupant immediately in the rear of the shifted or adjusted chair.

Attention is now directed to the modified form of the invention shown in Figures 12 and 13 of the drawings. Insofar as the chair base and frame is concerned, this part of the structure is the same as that shown and described in Figures 7 to 10 inclusive with consequently the same reference numerals I employed to identify identical parts. The obvious purpose of these two figures is to illustrate, in a broad way, the fact that a certain type of powering device may be utilized, if desired, and substituted for the power jack already described. In connection with this alternate construction, it will be seen that a suitable electric motor 78 is attached to and suspended from a bracket 79 on the under side of the seat 51 of the chair. The shaft of the motor is provided with a sprocket wheel to accommodate a sprocket chain 80, said sprocket chain being trained over a complementary sprocket wheel 81 fixedly mounted on the shaft 55 for purposes of rotating said shaft. In practice, an appropriate guard 82 is provided for the sprocket gears and chain assembly. As is evident to the reader, my invention as herein disclosed in ways to comprehend adaptations employing both hand and power actuated structures, the simpler embodiment being manually utilized, and the other embodiments being powered from suitable source of energy. The hydraulic jack means and electric motor means constitute examples of appropriate powering devices susceptible of use.

In the electric motor construction just described, it is obvious that the motor drives the sprocket means which in turn drives the shaft 55. This shaft controls the cogs 53 on opposite ends thereof which cogs mesh with the rack teeth 52.

I also desire to have the invention interpreted as comprehending suitable powering means which can be button controlled for purposes of more-or-less automatically operating the chair for receding and lifting purposes. This is an important phase of the invention and is herein shown in order to acquaint the reader with the range of the inventive ideas herein involved. I direct attention therefore to the lifting jack equipped chair construction shown in Figures 7 and 10 in particular. As illustrated in Figure 7 for example, the base plate of the rigid frame structure is denoted by the numeral 47 and this supports perpendicular uprights 48. The uprights are in the form of rectangular hollow casings with suitable arm rests 49 atop same. The uprights are interiorly constructed to provide co-acting L-shaped tracks 50 and 51, these having gear teeth 52 to accom-

modate pinions or gears 53 on horizontal shafts 54 and 55. These shafts operate in L-slots 54a and 55a and are mounted in suitably shaped depending legs or equivalent members 56 supported and carried by the seat 57 of the chair 58. The back rest is differentiated by the numeral 59 and, usually, is connected rigidly to seat 57, as is obvious. By providing the shafts and cogs or gears, the lifting and receding steps or motions of the chair are rendered positive and rigid.

In the drawings, I have shown, as one form of powering means, an air or hydraulic lifting jack 60. This comprises a cylinder 61 hingedly attached to the base as at 62 and hingedly attached to the underside of the seat of the chair, as at 63. Specifically, the cylinder is anchored at 62 and the piston elements 64, which operate in the cylinder are pivoted, at 63. This is an extensible type of jack as shown in dotted lines in Figure 7 and the hose line for supplying the fluid under pressure is denoted at 65.

It is contemplated that any suitable means may be employed for the purpose of controlling the operation of the jack 60 for purposes of applying force as necessary to shift and raise the chair in relation to the frame structure. Although, I have not worked out every detail of an absolutely foolproof control for the jack, I believe that the button and the valve arrangement shown somewhat diagrammatically in Figure 11 will suffice. I mention this because Figure 11 has been utilized to avoid the necessity of showing, in the other figures the complicated arrangement of pipe lines. What I am primarily interested in is the lifting and lowering jack and the chair structure shown in Figure 7 with any suitable button controlled device for operating the same. However, as stated, Figure 11 may be necessary to facilitate an understanding of one arrangement of button control structure. Here the hose line 65 is connected with a main button 67 which is positioned on the arm rest shown in Figures 7, 8 and 9. The button proper is indicated at 68 and is adapted to be depressed by the occupant of the chair. In so doing, it operates a spring returned valve 69 which controls the supply of fluid under pressure through the line 70 from a compressor or other source (not shown). This is possible because at the time the other valves in the line 70 are open. Incidentally, the line 71 denotes the return pipe to the compressor. This closes off when the line 70 is open and is opened when line 70 is closed by the valve 69. It follows that under normal circumstances, if the occupant of the chair desires to operate the lifting jack all that he does is to press the button 68 located conveniently on one of the arm rests. It is believed that this method of raising and lowering the chair is clear. However, to go into further foolproofing phases, it will perhaps be necessary to utilize extra safety control buttons or valve devices such as for example at 72 and 73. These are of duplicate construction and the buttons are denoted at 74 and 75. They are spring returned and also function as valves as is brought out in section in Figure 11. There will be one button, as said before, on one arm rest and another on the other arm rest and they will preferably be positioned for convenient use by a passer as shown in Figures 7, 8 and 9. The idea is that there will perhaps be instances where a passer will want to cut out the operation of the lifting jack upon his own initiative to avoid unnecessary collision between passers and chair

occupants. So for the convenience of a passer the buttons 74 and 75 are provided to close off the supply of fluid under pressure to the lifting jack. It is also quite possible that an auxiliary device will have to be used on the back-rest of each chair. This will be in the form of a T-shaped actuator or the like as indicated at 76 in Figure 11. This is positioned as shown in Figure 7, near the top of the back-rest of the chair so that a person who may be trapped while passing in the passage in the rear of the chair can take it upon himself to catch hold of the T-shaped device 76 and close off the valve 77 in the line to prevent the chair from coming back on him when in an inopportune or otherwise unsafe position. It follows therefore, that button controlled valve devices are provided in the fluid supply lines and are operable from front and rear of the chair and that these valve devices are for passers to utilize, if necessary, independently of the occupant of the chair. I am primarily interested in the main control button or device 67 in the fluid supply line for regulating the flow and return of fluid in the supply line and for regulating the flow and return of fluid to the lifting pump. I have included the auxiliary devices 72, 73 and 77 as precautionary appliances and have not particularly detailed the construction and arrangements since they are auxiliary and perhaps superfluous devices. In the construction just described, it is obvious that by turning on the fluid, so to speak, the jack is operated and the jack in turn, lifts the chair from the normal position seen in Figure 7, to the dotted line position also there shown. When the pressure is off, the chair returns to its normal position.

By way of summation, it is to be stressed that I am least concerned with the manually controlled chair of Figures 1 to 6 inclusive and am, therefore, primarily concerned with the form of chair disclosed in Figures 7 to 13 inclusive. In the latter figures, I disclose two embodiments of powering devices, one a hydraulic lift, and the other an electric motor (Figures 7 to 11 on the one hand and Figures 12 and 13 on the other hand). In reference to these powering devices or units, I contemplate the provision, in actual practice, of any suitable powering devices for lifting and lowering the chair as a unit. It follows that the essence of the invention has to do with a shiftable theatre chair construction, characterized by frame means fixedly attached to a floor or other stationary foundation, a chair which is made up of a seat and back rest, the back rest in substantially fixed relation to the seat, and appropriate means, preferably that disclosed in Figures 7 to 13, which serves to anchor and thus movably fasten the chair to the frame means, said latter means being carried by the chair and having slidable connection with the frame means and causing the seat to rise (1) vertically to a predetermined elevation, and then (2), to shift rearwardly in a horizontal plane, the seat remaining on an even keel and, therefore, constantly level and parallel in relation to the floor during the up and back movements.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and 75 rearrangements of parts may be resorted to in

actual practice so long as no departure is made from the invention as claimed.

What I claim is:

1. A theatre chair of the class described comprising a stationary base having uprights provided with vertically disposed L-shaped tracks, a liftable and lowerable chair situated between said uprights and including a seat and relatively fixed back rest, said seat being provided with depending leg members parallel to said uprights, shafts mounted for rotation in the lower portions of said leg members and provided on their outer ends with fixed cogs operable in said tracks, said tracks having rack teeth ranging from end to end, said cogs being geared by said teeth for positively feeding said shafts upwardly and rearwardly, and forwardly and downwardly in said tracks, and means for rotating and driving at least one of said shafts.

2. A theatre chair of the class described comprising a stationary base having uprights provided with vertically disposed L-shaped tracks, a liftable and lowerable chair situated between said uprights and including a seat and relatively fixed back rest, said seat being provided with depending leg members parallel to said uprights, shafts mounted for rotation in the lower portions of said leg members and provided on their outer ends with fixed cogs operable in said tracks, said tracks having rack teeth ranging from end to end, said cogs being geared by said teeth for positively feeding said shafts upwardly and rearwardly, and forwardly and downwardly in said tracks, an electric motor mounted on the underside of said seat and liftable and lowerable with the seat, and an operating connection between said motor and one of said shafts.

3. A liftable and receding theatre chair comprising a stationary horizontal base having a pair of spaced parallel uprights, each upright being a hollow casing and being provided interiorly with a pair of complementary L-shaped tracks, each track embodying a vertical branch and an elevated rearwardly directed horizontal branch and said branches being provided with rack teeth, the inner opposed walls of the respective uprights being provided with pairs of L-shaped slots and the respective slots being in registry with coacting forward and rearward tracks, a chair situated between said uprights and embodying a horizontal seat and a vertical back rest fixed to the rearward end of said seat, leg members fixed to and depending from the under side of said seat and disposed in spaced parallelism to the inward slotted walls of said uprights, a pair of horizontal shafts disposed between the respective legs

and journaled for rotation in bearings provided therefor in the lower end portions of said legs, the end portions of the respective shafts extending through the adjacent L-shaped slots and projecting for operation into the respective forward and rearward tracks, and a pinion fixedly mounted on the end portions of the shafts and in mesh with their respective rack teeth.

4. The structure specified in claim 3, and an electric motor secured to the underside of said seat, and sprocket and chain means affording a constant driving and operating connection between said motor and one of said shafts.

5. A liftable and receding theatre chair comprising a stationary horizontal base having a pair of spaced parallel uprights, each upright provided with an L-shaped rack embodying a vertical branch and an elevated rearwardly directed horizontal branch, a chair situated between said uprights and embodying a horizontal seat and a vertical back rest fixed to the rearward end of said seat, leg members fixed to and depending from the underside of said seat and parallel to the inward surfaces of said uprights, a horizontal shaft mounted for rotation in bearings provided therefor in said leg members, the end portions of said shaft being in close proximity to the respective racks, and pinions fixed on said end portions and in mesh with their respective racks, said uprights being in the form of hollow casings wholly enclosing said racks, the inner vertical walls of said casings having L-shaped slots in registry with the coacting L-shaped racks, and the end portions of said shaft extending through and being operable in the L-shaped slots.

ELIAS S. DIEHL.
